STONE PICKER

Louis Schema, Kiel, Wis.

Application June 6, 1935, Serial No. 25,273

3 Claims. (Cl. 55—17)

This invention appertains to farm and like equipment, and more particularly to novel means for picking up and removing stones from fields.

One of the primary objects of my invention is to provide an improved stone gatherer, which can be easily drawn over the ground, and which will effectively uproot and gather surface stones and convey the same to a suitable hopper on the frame, which can be dumped at preferred intervals on the ground into piles, or into carts, so that the stones can be carried to a desired remote point.

Another salient object of my invention is to provide a stone gathering machine, including a main frame mounted upon a suitably weighted land roller and carrying an endless conveyor, and a pivoted supplemental frame, with means for adjusting the position of the supplemental frame relative to the ground and the main frame, whereby the depth of penetration of the uprooting prongs can be controlled.

A further object of my invention is the provision of ground runners carried by the supplemental frame, having resilient supporting arms for engaging the front end of the main frame, with novel means for carrying the stones uprooted by the prong associated with the supplemental frame to the rear of the main frame and into the hopper carried thereby.

A further object of my invention is the provision of means under the control of the operator for dumping the hopper at desired intervals.

A still further object of my invention is to provide an improved stone gatherer of the above character, which will be durable and efficient in use, one that will be simple and easy to manufacture, and one which can be placed upon the market at a reasonable cost.

With these and other objects in view, the invention consists in the novel construction, arrangement, and formation of parts, as will be hereinafter more specifically described, claimed, and illustrated in the accompanying drawing, in which drawing:—

Figure 1 is a central longitudinal section through my improved rock gatherer.

Figure 2 is a fragmentary side elevation of my improved stone gatherer, showing the rear end thereof.

Figure 3 is a fragmentary top plan view of the improved device, showing the front end thereof, the draw-bar being shown broken away and in section.

Figure 4 is a fragmentary transverse section

taken on the line 4—4 of Figure 1, looking in the direction of the arrows.

Figure 5 is a similar view taken on the line 5—5 of Figure 1, looking in the direction of the arrows.

Referring to the drawing in detail, wherein similar reference characters designate corresponding parts throughout the several views, the letter A generally indicates my improved stone gatherer, which comprises a main frame 10. This frame 10 includes a pair of spaced, longitudinally extending main beams 11, which can be connected together and braced in any desired manner. The extreme rear ends of the main beams 11 have secured thereto the depending hopper 12 for receiving the gathered stone, and this hopper is provided with an inclined rigid bottom wall 13, and a swinging dump bottom gate 14, which is also arranged at an angle to the horizontal. This gate 14 is normally maintained in a closed position by means which will be later set forth.

Arranged in advance of the hopper 12 is a supplemental frame 15. This supplemental frame 15 embodies a pair of spaced parallel bottom beams 16, and a pair of top spaced parallel frame beams 17. Rigidly secured to the lower surface of the top frame beams 17 is a bed plate 18 over which the gathered rocks are drawn and elevated. Depending from the main beams 11 adjacent to the front end of the hopper 12 are bearing brackets 19, which receive and support the transversely extending shaft 20. The rear ends of the supplemental frame beams 16 and 17 carry independent bearings 21, which are rockably mounted on the cross shaft 20, whereby said pairs of supplemental frame beams 16 and 17 can swing independently of one another relative to the main frame beams 10. The lower pair of supplemental frame beams 16 are rigidly connected together by transversely extending slats 22, on which the bottom plate 18 carried by the supplemental frame beams 17 normally rests. The extreme front ends of the supplemental frame beams 17 carry forwardly and downwardly projecting rock-digging prongs 23, and these prongs can be rigidly bolted or riveted to a cross bar 24' connected to said beams 17.

Disposed in front of and below the hopper 12 is a transversely extending land roller 24, on which the rock gatherer travels. This roller 24 is utilized instead of ground wheels, and is preferably of a weighted character. An axially disposed axle 25 is carried by the land roller 24, and the ends of the axle are rotatably mounted

in side bearing brackets 26, which are rigidly bolted to the lower supplemental frame beam 16 adjacent to the rear terminals thereof.

The front terminals of the lower supplemental frame beams 16 carry longitudinally extending, ground-engaging runners 27, and these runners support the front end of the machine. The forward ends of the runners 27 are provided with resilient arms 28, the terminals of which extend 10 under and support the forward ends of the main frame beams 11.

From the construction so far, it can be seen that the stone gatherer is supported by front runners 27, and the ground roller 24, and that the 15 prongs 23 pick up the rocks during the travel of the machine. The rocks picked up by the prongs 23 are conveyed back over the bed or bottom plate 18 to the hopper 12 by an endless conveyor 29. The conveyor 29 includes a pair of spaced endless 20 sprocket chains 30, the opposite ends of which are trained over front and rear pairs of sprocket wheels 31 and 32.

The front pair of sprocket wheels 31 are keyed on or otherwise secured to a front cross shaft 25 33 rotatably mounted in suitable bearings carried by the front ends of the main frame beams 11. The rear pair of sprocket wheels 32 are keyed or otherwise secured to a cross shaft 34, the 30 terminals of which are rotatably mounted in bearing blocks 35 carried by the main frame beams 11 adjacent to the rear ends thereof. The sprocket chains 30 carry cross flights 35 at spaced intervals, and these cross flights may include transversely extending bars 36 carrying a plurality of equidistantly spaced curved teeth 37. The ends of the bars 36 are rigidly connected to laterally extending clips 38 carried by certain 35 links of the endless chains 30.

To bring about the proper driving of the endless conveyor 29, the rear shaft 34, and the main axle 25, have keyed respectively thereto sprocket wheels 39 and 40. The sprocket wheel 40 is of a considerably greater size than the sprocket wheel 39, and these wheels are operatively connected by a drive sprocket chain 41. Obviously, 45 during the travel of the machine over the ground the conveyor will be driven, and the teeth 37 of the flights will scrape by the prongs 23 and over the bed-plate 18, and carry the gathered rocks into the hopper.

Means is provided for adjusting the position of the bottom supplemental frame beams 16 relative to the main frame beams 11, and to the ground, and this means consists of overlapping brackets 42 and 43 carried respectively by the main frame beams 11 and the supplemental beams 16. The overlapping portions of the brackets are adjustably connected together in any desired manner. This will regulate the depth 60 of penetration of the prongs 23 into the ground.

The machine can be drawn over the ground in any desired way, such as by draft animals, or by a tractor, and any conventional type of draw-bar 44 can be connected with the frame. 65 In the present illustration the draw-bar 44 includes depending side arms 45, the lower terminals of which are rigidly bolted to the supplemental beams 16. The intermediate portions of the arms 45 are adjustably connected to the main frame beams 11, and these beams can carry outwardly extending bolts received within slots formed in said arms 45.

No normally maintain the gate 14 of the hopper in its closed position, pivoted latches 46 are provided. The rear ends of these latches are rigidly

secured to a rock shaft 47 mounted in bearings carried by the inclined bottom wall 13 of the hopper. By locking the shaft 47, the latches 46 can be moved into and out of operative engagement with the gate 14. To facilitate the 5 operation of the rock shaft 47, a hand lever 48 is rigidly connected to this shaft. A contractile coil spring 49 connects the hand lever 48 with a part of the supporting frame, and functions to normally hold the latches 46 in their elevated position, and in engagement with the gate 14. When the hopper is loaded with stones, the lever 48 can be swung in a clockwise direction, (see Figure 2 of the drawing), which will 10 throw the noses of the latches 46 below the front edge of the gate, and allow the gate to swing open under the weight of the rocks. The rocks can either be dumped in piles, or can be dumped into carts placed under the hopper.

From the foregoing description, it can be seen 20 that I have provided an exceptionally simple and efficient machine for picking up and gathering rocks from fields, and like places.

Changes in details may be made without departing from the spirit or scope of this invention, but what I claim as new is:—

1. A stone gatherer comprising a main frame including a pair of spaced parallel, longitudinally extending beams, a supplemental frame including pairs of upper and lower spaced parallel beams, means rockably supporting the rear ends of the upper and lower beams of the supplemental frame from the main frame beams, ground-engaging means carried by the opposite ends of the lower supplemental frame beams, 35 digging prongs carried by the forward ends of the upper supplemental frame beams, means adjustably connecting the main frame beams to the lower supplemental frame beams, an endless conveyor carried by the main frame beams for conveying rock picked up by the prongs to the rear end of the machine, and means for receiving the rock from the conveyor.

2. A rock-gathering machine comprising a main frame including a pair of spaced parallel main beams, a supplemental frame including a pair of lower beams and a pair of upper beams, a transversely extending shaft carried by the main beams, means rockably mounting the rear terminals of the upper and lower pairs of supplemental beams to the shaft, a land roller rotatably carried by the lower supplemental beams adjacent to their rear ends, a pair of ground runners carried by the forward ends of the lower supplemental beams, resilient supporting arms 55 on said runners engaging the front ends of the main beams, means adjustably connecting the main frame beams and the lower supplemental frame beams together, digging prongs carried by the upper supplemental beams, a longitudinally extending bed-plate carried by said upper supplemental beams, an endless conveyor for carrying rock picked up by the prongs to the rear end of the machine, means for receiving the rocks from the conveyor, and means for driving 60 the conveyor from the land roller.

3. A rock-gathering machine comprising a main frame including a pair of spaced parallel main beams, a supplemental frame including a pair of lower beams and a pair of upper beams, 70 a transversely extending shaft carried by the main beams, means rockably mounting the rear terminals of the upper and lower pairs of supplemental beams to the shaft, a land roller rotatably carried by the lower supplemental beams 75

adjacent to their rear ends, a pair of ground runners carried by the forward ends of the lower supplemental beams, resilient supporting arms on said runners engaging the front ends of the main beams, means adjustably connecting the main frame beams and the lower supplemental frame beams together, digging prongs carried by the upper supplemental beams, a longitudinally extending bed-plate carried by said upper supplemental beams, an endless conveyor for carry-

ing rock picked up by the prongs to the rear end of the machine, means for receiving the rocks from the conveyor, means for driving the conveyor from the land roller, said rock-receiving means including a hopper having a pivoted bottom gate, and manually controlled rigid means for normally maintaining the gate in a closed position.
